CLAIM

The ornamental design for a suspended tissue-box holder assembly, as shown and described.

DESCRIPTION

FIG. 1 is a top-front-left perspective view of a suspended tissue-box holder assembly showing my new design;
FIG. 2 is a bottom-rear-right perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is an enlarged right elevational view thereof;
FIG. 8 is an enlarged left elevational view thereof;
FIG. 9 is a top-front-left perspective view thereof, showing the suspended tissue-box holder assembly in use with environmental subject matter of an exemplary waste container and inflatable riser;
FIG. 10 is a bottom-rear-right perspective view thereof;
FIG. 11 is an enlarged cross-sectional view taken along line 11-11 in FIG. 4;
FIG. 12 is a top-front-left perspective view thereof, shown further in use with exemplary environmental subject matter of vehicle seats;
FIG. 13 is a front elevational view thereof; and,
FIG. 14 is an enlarged cross-sectional view taken along line 14-14 in FIG. 13.
The broken lines shown in the drawings represent both portions of the suspended tissue-box holder assembly as well as environmental structure. All broken lines in the drawings 35 form no part of the claimed design.
